JOHN M. PECK, OF VICTOR, NEW YORK, ASSIGNOR TO THE LOCKE INSULATOR MFG. CO.,
OF VICTOR, NEW YORK, A CORPORATION OF NEW YORK.

STRAIN-INSULATOR.

1,251,097.

Specification of Letters Patent. Patented Dec. 25, 1917.

Application filed January 25, 1917. Serial No. 144,346.

To all whom it may concern:

Be it known that I, JOHN M. PECK, of Victor, in the county of Ontario and State of New York, have invented certain new and 5 useful Improvements in Strain-Insulators; and I do hereby declare the following to be a full, clear, and exact description of the same, reference being had to the accompanying drawings, forming a part of this specification, and to the reference-numerals marked 10 thereon.

My invention relates to insulators of the type employed for supporting high tension and heavy electric conductors which frequently 15 require being suspended by a series of insulating units attached one to the other and commonly known as strain insulators, and it is my object to afford an efficient construction that can be manufactured and assembled at a reasonable cost. A further 20 purpose is to utilize the fewest possible number of parts and also to so connect the insulating material with the connecting members as not to weaken the insulating material and 25 to impart maximum strength and resisting force to the unit as a whole. To these and other ends the invention consists in certain improvements and combinations of parts all as will be hereinafter more fully described, 30 the novel features being pointed out in the claims at the end of the specification.

In the drawings:

Figure 1 is a sectional view with the parts in elevation showing the application of my 35 invention to a well-known type of strain insulator, with the parts in the initial assembling position;

Fig. 2 is a sectional view similar to Fig. 1 with the parts completely assembled;

Fig. 3 is a sectional view on line 3^a—3^a of Fig. 1;

Fig. 4 is a sectional view on the line 4^a—4^a of Fig. 2;

Fig. 5 is a sectional view on the line 5^a—5^a of Fig. 1, and

Fig. 6 is a sectional view on the line 6^a—6^a of Fig. 3.

Similar reference characters in the several figures indicate the same parts.

50 In the construction shown in the drawings, which it will be understood are intended merely to illustrate a possible embodiment of the invention in practical form, there is shown a usual form of insulating 55 section or portion including the skirt portion

1 and the upper or body portion 2 which latter is hollow and provided interiorly and exteriorly with annular locking grooves or channels 3 and 4 respectively, the inner groove 3 being disposed slightly spaced from the innermost surface 5 while the outer groove 4 is slightly spaced above the skirt portion 1. 6 designates a usual type of cap carried by the insulating portion and provided with the eye 7 by which it is connected to the adjacent insulating unit, the cap 6 and the rod or pin 8 constituting the two connecting members, usually formed of metal and affording means for tying or connecting to the adjacent insulating units disposed above and below the one shown. The cap 6, according to my present invention is provided at its lower edge with an internal annular locking groove or channel 9 and adjacent thereto immediately above is a secondary groove 10, larger and of greater diameter. The cap is also provided with openings 11 to permit access from the exterior to within the secondary groove 10. In the assembling of the cap upon the body of the 80 insulating section I employ two or more curved rods 12 formed of stiff metal, and these are positioned within the secondary groove 10, substantially in the manner shown in Fig. 5. With the locking rods 12 85 thus arranged in the groove 10, the cap is placed upon the insulating section in the position shown in Fig. 1. Any suitable instrument is then inserted through the openings 11 to force the locking rods into the 90 groove 4 until they assume the position shown in Fig. 6, and the cap can then be elevated until the locking rods 12 engage the groove 9 in the manner shown in Fig. 2. In order to hold the parts in this position and 95 relatively fixed, I employ retaining means in the form of threaded pins 13 which are inserted through suitable threaded openings in the cap, and brought into engagement with the locking rods 12, or any other retaining means for holding the rods in this relation. Preferably, the rods are so proportioned that when in final adjusted position they form a continuous ring, as shown in Fig. 6, with their adjacent ends in contact 105 with each other and of the same diameter as the groove 4, and thus a continuous and uninterrupted line of contact is had between the metal cap and the body portion of the insulating material, and the strain upon the 110

insulating material is equally distributed throughout the same. This adds greatly to the strength and durability of the structure. The same principle is applied to the attachment of the insulating section and the inner connecting member which has already been referred to as 8, and is provided with a locking shoulder or groove 14 and adjacent thereto a secondary groove or channel 15 which is deeper and of less diameter. The locking member employed in this particular relation is in the form of a spring or split ring 16 which is of such size that when in normal or uncontracted position, it fits closely in the groove 3 and is immovable therefrom. In the assembling of the pin 8, the locking ring 16 is positioned in the groove 15 as shown in Fig. 4 and is contracted by engagement with the inner wall 17 of the insulating section. The pin, with the locking ring thus contracted, is forced inwardly until the ring reaches the annular locking groove 2 into which it expands, as shown in Figs. 2 and 4. Upon the application of tension to the pin 8, it is withdrawn until the locking groove or shoulder 14 engages the ring 16, as shown in Fig. 2, and the parts are held permanently in this relation.

The structure shown and described may be modified without departing from the invention, and I intend covering by this application any changes or different forms coming within the purpose of my improvement and the scope of the appended claims.

35 I claim as my invention:

1. In a strain insulator, the combination with a section of insulating material having an annular locking groove, of a metallic connecting member having an annular locking groove adapted to be alined with the aforesaid groove and a secondary groove or channel adjacent to the locking groove on the connecting member, and a stiff curved locking rod adapted to be positioned in the secondary groove of the connecting member during the assembling operation and, when finally positioned, to coöperate with the recess formed by the locking grooves on the insulating section and connecting member 45 to hold them against relative separating movement.

2. In a strain insulator, the combination with a section of insulating material having an annular locking groove, of a metallic connecting member having an annular locking groove adapted to be alined with the

aforesaid groove and a secondary groove or channel adjacent to the locking groove on the connecting member, and a stiff curved locking rod fixedly held in the groove of the insulating section and coöperating with the groove of the connecting member so as to prevent removal of the latter.

3. In a strain insulator, the combination with a section of insulating material having an annular locking groove, of a metallic connecting member having an annular locking groove adapted to be alined with the aforesaid groove and a secondary groove or channel adjacent to the locking groove on the connecting member, and a series of stiff curved locking rods adapted to be positioned in the secondary groove of the connecting member during the assembling operation and, when finally positioned, to coöperate with the recess formed by the locking grooves on the insulating section and connecting member to hold them against relative separating movement.

4. In a strain insulator, the combination with a section of insulating material having an annular locking groove, of a metallic connecting member having an annular locking groove adapted to be alined with the aforesaid groove and a secondary groove or channel adjacent to the locking groove on the connecting member, a series of stiff curved locking rods adapted to be positioned in the secondary groove of the connecting member during the assembling operation and, when finally positioned, to coöperate with the recess formed by the locking grooves on the insulating section and connecting member and acting to retain them against relative separating movement, and retaining means carried by the connecting member and engaging the locking rods to retain them in the grooves of the insulating section.

5. In a strain insulator, the combination with a section of insulating material having an annular locking groove, of a metallic cap having a locking groove at its lower edge and a secondary groove adjacent to the locking groove, a plurality of locking rods adapted to be positioned in the secondary groove during assembling and to coöperate with the recess formed by the locking grooves when finally positioned, and retaining pins carried by the cap and engaging said locking rods to prevent their removal from the groove of the insulating section.

JOHN M. PECK.
